[57] CLAIM

The ornamental design for a fishing reel pouch, as shown and described.

DESCRIPTION

FIG. 1 is a perspective view of a fishing reel pouch showing my new design;

FIG. 2 is a front elevational view thereof, the rear elevational view being a mirror image thereof;

FIG. 3 is a top plan view thereof; and,

FIG. 4 is a side elevational view thereof.

The characteristic feature of the design resides in the hidden particular arrangement of the dual drawstring closure.
